(57) **CLAIM**

The ornamental design for a label area of flash memory drive, as shown and described.

DESCRIPTION

FIG. 1 is a side, top, perspective view of a label area of flash memory drive with housing, cap housing and clip portion thereof shown in phantom lines;

FIG. 2 is a top view thereof, the bottom view being a mirror image thereof; and,

FIG. 3 is a side, top, perspective exploded view of the label area of a computer insert with one end cap removed.

1 Claim, 1 Drawing Sheet

FIG. 3

FIG. 2
